UNITED STATES PATENT OFFICE.

VALENTINE NEWBAUER, OF MINNEAPOLIS, MINNESOTA.

VERTICALLY-RISING AEROPLANE.

Application filed September 15, 1924, Serial No. 737,748. Renewed November 14, 1925.

To all whom it may concern:

Be it known that I, VALENTINE NEWBAUER, a citizen of the United States, residing at Minneapolis, in the county of Hennepin and State of Minnesota, have invented certain new and useful Improvements in Vertically-Rising Aeroplanes, of which the following is a specification.

This invention relates to the art of aeronautics and the main object is to provide an aeroplane, of the vertically rising type, in which propellers are used in the dual capacity of controlling and determining the vertical as well as the horizontal flight and position of the machine. A further object is to provide means whereby such propellers may be utilized in co-operation with the well-known ailerons and other controlling members of the machine to insure both longitudinal and transverse or lateral stabilization. A further object is to so arrange the propellers with respect to wings, tail and aileron controls, that the craft may be volplaned to the earth in the event that the driving motor thereof should for any reason become inoperative. Further and more specific objects will be disclosed in the course of the following specification, reference being had to the accompanying drawings, wherein:

Fig. 1 is a side elevation of an aeroplane embodying my invention.

Fig. 2 is a top or plan view of the aeroplane shown in Fig. 1, a right end portion being broken away.

Fig. 3 is a front elevation of the machine on an enlarged scale, and with the left end portion thereof broken away.

Referring to the drawings more particularly and by reference characters, A designates the body or fuselage of an aeroplane having a landing gear B, a tail skid C, an upper set of wings D, lying in the same plane, ailerons E, wing struts F; and a tail group G, consisting of a fixed rudder or fin 4, a hinged rudder 5, rigid stabilizers 6, and hinged elevators 7. The parts of the machine thus far described and their braces are of common and well known construction, as is also the controlling method for the moving parts as E, 5 and 7, and therefore a further detailed description of such expedients will be dispensed with.

The inner struts F are supported from the fuselage proper, while the outer struts F are supported upon transversely extending beams 8 which project out from the fuselage

in parallel positions to and under the wings D. At intermediate positions upon the beams 8 are mounted a pair of propellers H, later to be described, which rotate in substantially horizontal planes, on vertical axes, one at each side of the fuselage, and are driven by transversely arranged and housed shafts 9, from the engine (not shown) in the fuselage. In Fig. 3 the dotted lines 10 indicate radiators for the cooling system of the engine, and they are arranged horizontally under the inner sweeps of the propellers H so as to be cooled thereby. A pair of auxiliary ailerons 11 are arranged for tilting movement at the outer ends of the wing structures, in substantially the operating plane of the propellers H, and are connected by bars 12 to the ailerons E so as to be operated thereby and simultaneously therewith.

A head wing J, of novel construction, is arranged in advance of the propellers H and extends completely across the front of the machine. This wing is tiltably mounted upon a shaft 13 which is carried by braces 14 extending forwardly from rigid parts of the ship. The head wing is provided with arms 15 and 16 to which are attached cables 17, leading to the cockpit, where they are operated in any suitable manner, by the pilot, to control the tiltable position of the wing. It will be noted, particularly in Fig. 1, that the head wing J is substantially triangular in cross section, having a flat surface 18, a convex surface 19, and a concave surface 20.

The propeller H is of the two blade type in which the oppositely disposed blades are curved transversely in such a manner that the surfaces 21 will affect a downward or axial air thrust. At the outer ends of these radial propeller blades are provided a pair of transversely angled and vertically disposed blades 22, which are designed to create a radial thrust to expel air centrifugally from the propeller. These blades 22 are adjustably mounted at the ends of the main propeller arms, by braces 23, so that their transverse angle may be adjusted as the distance of sweep, speed of the propellers or desired speed of the machine may require.

Now when the machine is to take off or start upon its flight, the head wing J is adjusted to its inactive or dotted line position as shown in Fig. 1. The propellers H are rotated by the engine or usual power unit, whereupon the machine will start its ascent by reason of the downward thrust of the

propeller surfaces 21. There will be no particular effort or means to propel the machine forward. The radial or centrifugal current of air affected by the blades 22 will be thrown out to all sides with no motive effect. Such current, at the front of the craft, will be merely thrown over the curved surface 19 of the head wing. At the sides and rear of the machine, however, this current will be directed into the lower ailerons 11 and into the tail group G, with a result that the pilot will be able to utilize the stabilizing members 11, 4, 5, 6 and 7, to affect the proper equilibrium and balance of the machine when in either horizontal or vertical motion.

To change the movement of the aeroplane from a vertical to a horizontal direction the operator now merely shifts the head wing J 20 to the full line position shown in Figs. 1, 2 and 3. The forwardly directed current of air from the blades 22 is now directed against the head wing (instead of over it) and is diverted by the curved surface 20 25 downwardly and rearwardly thus creating a rearward thrust, which with the already existing direct rearward thrust at the rear of the machine, causes the machine to move forwardly in a horizontal direction. In normal forward flight the machine will be slightly tilted forwardly from a horizontal position with a result that the propeller surfaces 21, though still imparting a vertical lifting 30 tendency will also create a partial rearward thrust in moving the machine forwardly.

Should the power unit of the machine for any reason become inoperative, so that the propellers cannot be operated, the machine may then be volplaned to the earth, as with 40 any other aeroplane, in which event sufficient gliding or surface resistance and control will be affected by the wings D, the ailerons E and 11, the head wing surface 18, and the horizontal tail group members 6 and 7.

It is understood that various suitable modifications may be made in the general design and structural details of the machine as it is herein illustrated and described, provided, however, that such modifications come 45 within the spirit and scope of the appended claims.

Having now therefore fully shown and described my invention, what I claim to be new and desire to protect by Letters Patent is:

1. An aeroplane comprising a fuselage, supporting wings therefor, a pair of horizontally arranged propeller members at the sides of the fuselage and under said wings, adjustable stabilizing members arranged in the operating planes of said propellers, and an adjustable deflecting member arranged in advance of the propeller members.

2. An aeroplane having a number of horizontal stabilizing members and means for

adjusting the same, of means for affecting a downward thrust of air to cause the aeroplane to rise vertically, and means for affecting a horizontal thrust of air rearwardly into some of said stabilizing members, and 70 transversely or outwardly into other stabilizing members.

3. An aeroplane consisting of a fuselage having a tail group of stabilizing and control members, a pair of propeller members mounted on substantially vertical axes for rotation in substantially horizontal planes at opposite sides of the fuselage, and ailerons arranged laterally beyond the propellers to affect lateral stabilization, said tail group and ailerons being positioned so as to receive horizontal thrusts of air delivered by the propeller members.

4. The combination with an aeroplane having horizontal supporting surfaces, of a pair of laterally arranged propellers mounted upon vertical axes for movements in a horizontal plane, said propellers having surfaces for creating both downward and horizontal or radial thrusts of air, and manually controlled adjustable means for diverting the forward radial thrusts of air to a rearward and downward direction.

5. The combination with an aeroplane having horizontal supporting surfaces, of a pair of laterally arranged propellers mounted upon vertical axes for movements in a horizontal plane, said propellers having surfaces for creating both downward and horizontal thrusts of air, means for diverting the forward horizontal thrusts of air, and stabilizing members arranged to be acted upon by said horizontal air thrusts at the sides and rear of the aeroplane.

6. The combination with an aeroplane having a fuselage and horizontal supporting and stabilizing members, of means for creating a downward thrust of air to cause the machine to rise vertically, means for creating radial thrusts of air in horizontal planes at the sides of the machine, and a head member arranged forwardly on the machine to deflect the forward radial thrust of air so that the aeroplane will be propelled forwardly.

7. The combination with an aeroplane having a fuselage and horizontal supporting surfaces, of propeller members mounted at opposite sides of the fuselage, said propeller members having primary surfaces for creating downward thrusts of air, and having secondary surfaces for creating horizontal thrusts of air, some of said supporting surfaces being adjustable to affect stabilization and arranged to be acted upon by said horizontal air thrusts, and means for controlling said horizontal thrusts of air whereby the aeroplane will be actuated in a horizontal or forward direction.

8. The combination with an aeroplane

having a fuselage and horizontally disposed supporting and controlling members, of a pair of propeller members one disposed at each side of the fuselage, said propeller members having horizontally inclined surfaces for creating downward currents of air and having vertically inclined surfaces for creating radial horizontal currents of air, and adjustable means for deflecting the forward horizontal currents of air to cause the aeroplane to move forwardly when in flight.

9. The combination with an aeroplane fuselage, of wings extending transversely over the same and including primary ailerons, secondary ailerons arranged below the outer ends of the wings and operative simultaneously with the primary ailerons, stabilizing members at the rear end of the fuselage, a pair of propeller members mounted at opposite sides of the fuselage to

create radial air thrusts horizontally and having surfaces for creating axial air thrusts downwardly, and an adjustable head wing mounted in advance of the propellers to deflect the forward radial air thrusts.

25

10. The combination with an aeroplane, of a pair of propellers mounted upon substantially vertical axes, one at each side of the machine, said propellers having blades for creating downward air thrusts, and having adjustable secondary blades for creating horizontal radial air thrusts, stabilizing members arranged in the path of said radial air thrusts, and an adjustable head member arranged in advance of the propellers to deflect the forwardly directed horizontal air thrusts.
